W. L. STANLEY.

FASTENING MEANS FOR CAR DOORS AND WINDOWS.

APPLICATION FILED JULY 6, 1915. RENEWED MAY 16, 1916.

1,188,216.

Patented June 20, 1916.

FIG. 5. *Walter C. Stanley*
By *Vernon E. Knobell* his ^{Attorney}

UNITED STATES PATENT OFFICE.

WALTER L. STANLEY, OF NORFOLK, VIRGINIA.

FASTENING MEANS FOR CAR DOORS AND WINDOWS.

1,188,216.

Specification of Letters Patent. Patented June 20, 1916.

Application filed July 6, 1915, Serial No. 38,232. Renewed May 16, 1916. Serial No. 97,960.

To all whom it may concern:

Be it known that I, WALTER L. STANLEY, a citizen of the United States, residing at Norfolk, in the county of Norfolk and State 5 of Virginia, have invented certain new and useful Improvements in Fastening Means for Car Doors and Windows, of which the following is a specification.

My invention relates to an improvement 10 in fastening means for car doors and windows, the object being to provide a fastening with a seal which must be broken before the car door or window can be opened, thus betraying any clandestine entrance to the car.

15 It consists in a bolt adapted for use in connection with a hasp, and it has the double function of fastening the hasp and holding the door against the car body.

In the accompanying drawings:—Figure 20 1 is a fragmentary view of a portion of a car body and door showing my improved fastening means applied; Fig. 2 is an enlarged fragmentary horizontal view; Fig. 3 is a longitudinal sectional view through the 25 fastener; Fig. 4 is a top plan view; and Fig. 5 is a transverse section on the line 5—5 of Fig. 2.

A, represents the car body, and numeral 1 indicates the car door. The fastener is 30 secured to the car body, as shown in Figs. 1 and 2, with one edge in line with the door opening, and the hasp 2 is fastened preferably by means of a staple 3 to the car door 1.

The numeral 4 represents the casing of 35 the fastener, and 5 is the bolt fitted and adapted to slide therein, as illustrated in Figs. 2 and 5.

The casing has an inwardly-projecting stud 6, and the hasp has the usual slot 7 to 40 receive this stud, and a socket 8 in the bolt conforms to and fits the end of the hasp when the bolt is projected over the edge of the door 1, as shown in Fig. 2, thus tending to hold the hasp and preventing its rattling, 45 and consequently greatly lessening the wear which would otherwise result. The enlarged clearance space 21 in the outer end of the bolt 5 is provided to allow the hasp 2 to be placed over the stud 6 when the bolt is with- 50 drawn or in its normal position.

The bolt carries a gravity-pin 9, which normally rests on the bottom of the casing 4, as shown in Fig. 3, but which drops into an opening 10 in the bottom of the casing when 55 the bolt is projected to the position shown

in Fig. 2, as is clearly illustrated in Fig. 5. This gravity-pin 9 is entirely concealed, as shown in Fig. 5, so that access to it cannot be gained without breaking the seal. The seal is indicated by the numeral 11, and may 60 be of glass, clay, or any other frangible material, and bearing a legend, as shown in Fig. 3, such as the railroad, car number, and the like.

The seal 11 is dropped in place through a 65 slot 12 at the top when the bolt is drawn back to the position shown in Fig. 3, and the groove 13 which receives the seal is in registry with the slot 12, and the seal 11 is held in position when the bolt 5 is moved 70 outward by being covered by the sealed top of the casing 4.

The bolt is moved by means of the knob 14 working in the slot 15, see Fig. 1.

An open slot 16 straddles the stud 6, and 75 its closed inner end stops the further outward movement of the bolt 5 by striking against the stud 6, as does also the knob 14 by similarly striking the forward or closed end of the closed slot 15. A cotter 17 in 80 the gravity-pin 9 is provided as a means for lifting the pin out of the opening 10 when the seal has been broken, and the gravity-pin is to be raised and the bolt to be pushed into its casing when the hasp is 85 swung from the stud 6 and the door 1 is released.

While my invention is shown in connection with a sliding-door, as illustrated in Fig. 1, it is just as applicable to a hinged 90 door, and in that event it is necessary to swing the hasp 2 up out of the way, as shown in dotted lines in Fig. 1, and then drop it through the open slot 18 in the top of the casing, as illustrated in Fig. 4, and 95 thence over the stud 6.

To easily assemble the parts, the rear end of the casing 4 is left open as shown, but the bolts 19 which secure the fastener to the car body at one end are purposely in its 100 direct path where they prevent the bolt from sliding out. Other bolts 20, 20, at the top and bottom are used to securely fasten the fastener in place.

This improved fastener is simple, easy and 105 inexpensive to make, and is especially well adapted to the fastening of car doors and windows where it is preferred to use some form of hasp as the main fastening means.

I claim:

1. A fastener for car doors and windows, comprising a casing, a bolt, and a concealed gravity-pin carried by the bolt, and which automatically fastens the bolt when in one of its positions.
2. A fastener for car doors and windows, comprising a casing, a bolt, and a concealed gravity-pin carried by the bolt, and which automatically fastens the bolt when in one of its positions, and frangible means carried by the bolt over the gravity-pin which must be broken in order to gain access to the pin.
3. The combination with a hasp, of a fastener comprising a casing having a stud upon which the hasp is adapted to be placed, and a bolt slidably fitted within the casing, said bolt having a socket which receives the end of the hasp over the stud and holds it thereon, and means carried by the bolt for automatically locking it when in position to hold the hasp on the stud.
4. The combination with a car body and door and a fastener carried by the car body, and a hasp by the door, the fastener comprising a casing and a bolt slidably mounted therein, said bolt adapted to hold the hasp on a stud on the casing when the bolt is projected over the edge of the door, whereby the door is held in place against the car body and the hasp upon the stud.
5. The combination with a car body and door and a fastener carried by the car body, and a hasp by the door, the fastener comprising a casing and a bolt slidably mounted therein, said bolt adapted to hold the hasp on a stud on the casing when the bolt is projected over the edge of the door, whereby the door is held in place against the car body and the hasp upon the stud, and means
- carried by the bolt for automatically fastening it.
6. The combination with a car body and door and a fastener carried by the car body, and a hasp by the door, the fastener comprising a casing and a bolt slidably mounted therein, said bolt adapted to hold the hasp on a stud on the casing when the bolt is projected over the edge of the door, whereby the door is held in place against the car body and the hasp upon the stud, means carried by the bolt for automatically fastening it, and a seal also carried by the bolt which is locked therein when the bolt is projected and must be broken in order to gain access to release the automatic locking means.
7. A fastener for car doors and windows comprising a casing having an inwardly-projecting stud on its inner wall and having a horizontally-disposed open slot, and an opening through which the seal is shown on its outer wall, the casing open at opposite ends, of a bolt slidably fitted within the casing provided with a groove for the seal and having an open slot at one end which receives the stud, and provided with a socket which approximately fits the free end of the hasp and having a knob which slides in the open slot in the casing, the closed ends of the open slots in the bolt and casing limiting the movement of the bolt in one direction, and means for securing the fastening to the car body, certain of said means in the path of the bolt to prevent its withdrawal from the casing.

In testimony whereof I affix my signature.

WALTER L. STANLEY.
